UNITED STATES PATENT OFFICE.

WILLIAM McDANIEL, OF COLLINSVILLE, ILLINOIS.

BUILDING BLOCK.

Application filed November 22, 1920. Serial No. 425,769.

To all whom it may concern:

Be it known that I, WILLIAM McDANIEL, a citizen of the United States, residing at Collinsville, in the county of Madison and State of Illinois, have invented new and useful Improvements in Building Blocks, of which the following is a specification.

My present invention has reference to building construction.

10 My object is to construct the walls of a building from concrete or other plastic blocks, each of which has a central air space therethrough, pockets to the sides and ends of the air space to receive the binder there-
15 in, each of said blocks having a facing ar- ranged beyond one of the edges and one of the ends thereof and projecting beyond the other edge and end, the projecting portions being of a length greater than the distance
20 between the edges of the facings and the blocks, so that a suitable space for a binder will be arranged between the confronting ends of the courses of blocks, whereby no binder need be employed between the con-
25 tacting edges and ends of the facings of the blocks in the several courses of the wall.

A further object is the production of a building block which is so constructed and arranged as to permit of the same being laid
30 in courses by persons not particularly skilled in masonry or bricklaying.

A still further object is a building construction in which no mortar or similar binder will appear between the joints on the
35 outer faces of the blocks that constitute the same, wherein a dead air space is provided between the inner and outer faces of the blocks, and whereby a strong and damp- proof wall can be easily erected in a sub-
40 stantial manner.

A further object is the construction of a building in which blocks of a similar size and shape are employed, the only exception being in the outer ends of the corner blocks,
45 the construction being such as to permit of the wall being constructed from either the center or the corners thereof, the size and construction of the blocks permitting of the arrangement of one of the blocks between
50 any two or more of the blocks or laid in courses.

The foregoing, and other objects which will appear as the nature of the invention is better understood, may be accomplished by
55 a construction, combination and operative arrangement of parts, such as is disclosed

by the drawings which accompany and which form part of this application.

In the drawings:—

Figure 1 is a perspective view of a portion of a building constructed with blocks in accordance with this invention. 60

Figure 2 is a sectional view taken centrally of one of the openings providing a door or window-way between the courses of 65 blocks.

Figure 3 is a sectional view on the line 3—3 of Figure 1.

Figure 4 is a perspective view looking toward the inner face of one of the blocks. 70

Figure 5 is a similar view looking toward the outer face of the block.

Figure 6 is a perspective view looking toward one end of one of the corner blocks.

Figure 7 is a similar view looking toward 75 the opposite end of the corner block.

Figure 8 is a similar view looking toward the bottom of the corner block.

Figure 9 is a perspective view of the corner block for the courses to be erected 80 next to the corner block illustrated in Figures 6, 7 and 8.

Figure 10 is a similar view but looking toward the opposite side of the block.

In erecting a wall or building with plastic 85 blocks constructed in accordance with this invention, a suitable concrete foundation 1 is laid. The concrete, at the upper and outer edge thereof is formed with a depressed portion, the lower wall of which is indicated 90 by the numeral 3 and the side wall by the numeral 4, and the purpose of this arrangement of the foundation will be presently understood.

My improved building blocks may be reinforced, if desired, and while the same are preferably constructed of concrete the same may be formed of clay which is baked in the usual manner. 95

Except for the corner blocks, all of the 100 blocks are similarly constructed, and the only difference between the corner blocks of the superimposed courses is at the outer ends thereof and the arrangement of the facings which project from the body of the 105 blocks upon the opposite sides of the said corner blocks.

When constructed of concrete, the blocks are formed in a suitable mold and each of the blocks is of a similar size and shape 110 throughout.

Therefore, a description of one of the

blocks may be taken as equally applicable to the remaining blocks. Each of the blocks includes a rectangular body 4. The body 4 is centrally provided with an opening 5 therethrough. The opening provides an air space, and terminates a suitable distance away from the front and rear faces and the ends of the block. Each block, on both the top and bottom surfaces thereof is formed 10 with both longitudinal and transverse depressions 6 and 7 respectively, the said depressions providing pockets for the mortar which binds the courses together. Each block has on its outer surface an integrally formed rectangular facing 8. The facing is in the nature of a plate, and projects below the bottom of the block beyond one of the ends of the block. The projecting portion of the facings is of a greater length than 15 is the distance between the top and inner edge of the facings, indicated for distinction by the numerals 9 and 10, and the upper edge and inner edge of the said block. By this arrangement, it will be noted that the 20 confronting edges of the facing plates in the blocks of each of the series or courses, when in contacting relation, provide a space between the confronting ends of the said blocks, and in this space the mortar binder 25 is received. In like manner, the depending portions of the facings permit of the lower edges thereof resting on the shoulders 11 provided by the top edges on the facings of the next lower course of blocks; while a 30 mortar space is left between the upper and lower faces of the said courses of blocks.

Of course, the courses of blocks are broken, that is, the confronting ends of one course of blocks is disposed centrally between the blocks of the next course, but the air space in any of the blocks is of sufficient length as to provide a communication with the air space in the block directly above and directly below each block in all of the 45 courses.

The lowermost course of blocks have their projecting faces resting on the shoulder 2 and abut against the wall 3 of the foundation, suitable space, as heretofore set forth, 50 being provided for the reception of a binder between the foundation and the said blocks. As disclosed in Figures 1 and 2 of the drawings, door or window-ways may be provided by the employment of the end blocks. Each 55 of the end blocks is constructed in a manner

as previously described, except that one end of each of the said blocks has a projecting facing 12 that is in a line with the facing on the outer surface thereof, the lateral facing 12 receiving therein the upper corner portion 13 of the next series of blocks, either the upper or the lower series. The corner blocks of the referred to series have their ends provided with lateral facings 14, similar to the facings 12, but arranged upon the 60 opposite ends of the referred to corner blocks.

A building constructed with my improved blocks will have no mortar appearing on the outer face thereof. The facing plates of the 70 blocks may be suitably glazed or ornamented. The courses of blocks may be easily laid, and the vertical air spaces which are arranged in spaced relation to each other throughout the height and width of the 75 walls prevent dampness passing through the blocks, and it is thought that a further description of the improvement will not be considered necessary to those skilled in the art to which such inventions relate.

Having described the invention, I claim:—

In a wall construction, blocks arranged in superimposed courses having broken joints, said blocks having a rectangular body portion and provided with a centrally arranged opening of the same shape and said opening terminating inwardly from the outer edges a substantial distance, each block being provided on both its top and bottom surfaces thereof with longitudinal and transverse depressions and the ends of the longitudinal depressions are adapted to communicate with the respective ends of the transverse depressions providing an endless rectangular groove thereby and a mortar 85 pocket for binding the courses together, a plate formed integral with the front face of each block and substantially the same shape and size of said front face, the plate projecting below the bottom of each block 90 and beyond one of its ends thereof, and the end projection being the same length as the distance between the opposite end of the plate and the adjacent edge of the block, and the bottom projection being a greater 95 length than the distance between the top edge of the block and upper edge of the plate as and for the purpose specified.

In testimony whereof I affix my signature.

WILLIAM McDANIEL.
